UNITED STATES PATENT OFFICE

2,097,708

COLLAPSIBLE CONTAINER

Gustave A. Trost, San Francisco, Calif., assignor
to Fleishhacker Paper Box Company, San
Francisco, Calif., a corporation of California

Application September 14, 1936, Serial No. 100,692

3 Claims. (Cl. 229—31)

The present invention relates generally to boxes of the cardboard type, and more particularly to a box of the type and style generally termed foldable, knockdown or collapsible, which is constructed from a one piece blank.

An object of the invention is to provide a box that can be quickly and economically constructed, and which will fold flatly and be capable of use for various purposes in a simple and convenient manner.

Another object of the invention is to provide a folding box constructed from a single blank which can be expeditiously changed from a collapsed to an erected condition or vice versa in an expeditious manner.

Another object of the invention is to provide a foldable box wherein the folds reinforce and rigidly stay the corners and thus produce a box, which will withstand rough usage, and when filled will not disengage at the corners, as frequently occurs with prior art boxes of this character.

Another object of the invention is to provide a novel construction for a foil lined box which is particularly suited to the shipment of moisture containing articles, such as flowers and the like.

With the above and other objects in view, my invention consists in certain novel details of construction, combination and arrangement of parts which will be in part evident to those skilled in the art, and in part more particularly pointed out hereinafter.

In the accompanying drawings, wherein there is shown by way of illustration and not of limitation, a preferred embodiment of the invention;

Figure 1 is a perspective view of a box constructed in accordance with this invention in its closed condition,

Figure 2 is a developed plan view of a blank cut and scored in accordance with the present invention,

Figure 3 is a view showing the blank of Figure 2, partially folded and in its so-called collapsed position,

Figure 4 is a fragmentary view showing the bottom forming end of the box blank in its partially erected position,

Figure 5 shows the entire blank with the bottom portion of the box fully erected and the cover forming portion partially rotated into its box closing position, and

Figure 6 is a perspective view similar to Figure 1, showing the box blank as it approaches its final closed and locked condition.

As shown in Figure 1, the box, designated by

the numeral 10, constructed in accordance with this invention, is of rectangular shape, having a top and bottom, two sides and two ends which are formed from a single blank, and when folded provide a completely enclosed rectangular space. 5 The box 10 can be made of any foldable material, such as cardboard or the like, but where the box is to be used in the shipment of articles containing moisture, such as flowers, fruits, vegetables or like articles, I preferably construct the 10 box with a blank having a metal foil suitably attached to the side thereof, which forms the inside of the box. Such a box will be found to be impervious to any contained moisture, and as a result the box will last longer than will a box 15 which without the foil lining would absorb moisture and become weakened. For lightness I prefer to use an aluminium foil which can be adhesively attached to the cardboard stock from which the box forming blank is to be cut. When 20 the foil is applied to the material in this manner it will follow the folded surfaces and produce a container which will also have improved heat insulating properties. This latter advantage is attributable mainly to the heat reflecting character of the metal foil. 25

As shown in Figure 2 of the drawings, the one piece blank from which the box 10 is to be made, is cut and scored so as to form a bottom portion 11 with wall forming portions 12 at each side 30 thereof, and also a top portion 13 with side forming portions 14 at the sides thereof. Between the top and bottom portions 11 and 13 there is an end forming portion 15 and at the outer right hand end of the blank there is a second end 35 forming portion 16 from which there extends an inwardly foldable flap 17 that is adapted to be stapled upon the end portion 16, as will herein-after appear. At the ends of the portion 16 the blank is scored to complete a rectangular outline 40 at these corners of the blank, and extending outwardly in these rectangles there is provided a diagonal scored line 18. Along the sides of the blank and at the ends of the intermediate end portion 15, the blank is notched out as at 19 45 and scored lines are extended inwardly from these notches to the corners of the top and bottom portions 11 and 13. At the left hand end of the box forming blank there is a central or top closing flap 20 which is adapted to project at its 50 corners into slots 21 cut in the end forming portion 16 and at the end of each side forming portion 14 there is a similar but smaller box closing flap 22.

As shown in Figure 3 of the drawings, after 55

the box forming blank has been cut and scored as above described, the side wall forming portions 12 and 14 are folded inwardly upon the bottom and top portions 11 and 13 and the end flap 11 is stapled upon the inside of the end forming portions 16 in overlapping relation with the diagonally scored end portions of the sides 12. This is the condition in which the collapsible box constructed in accordance with this invention is delivered to a customer by the box manufacturer.

When the collapsed box blank described above is received by a customer and is about to be erected for use, the end forming portion 16 is elevated to its vertical position and the side forming portions 12 are thereby caused to raise, as indicated in Figure 4 of the drawings. As the end forming portion 16 is brought into its final vertical position, the flap forming portion 11, because of its stiffness, will snap down over the fold formed by the diagonal lines 18 at the corners of the blank and this portion of the box will be secured in its erected position.

Upon referring to Figure 5 of the drawings, it will be seen that after the above operation has been completed, the box may be closed by folding the top forming portion 13 and the end forming portion 16 clockwise over the box forming portion formed by the previously described operation. During this operation the diagonally scored 30 and notched portions 19 at the ends of the end forming portion 16 will fold inwardly so as to cause the three triangular portions to interlock and secure the box in its erected position at these corners.

35 To finally close the box as shown in Figure 6 of the drawings, it is then only necessary to bring the top portion 13 into its closed position and project the corners of the tab 20 into the slots 21, after which the closure tabs 22 can be inserted 40 into the recess formed at the corners of the box by the in-folded triangular portions formed by the diagonal scoring lines 10 previously described. As shown in this figure of the drawings, one corner of the box has been fully closed, and as a 45 final closing operation it is now only necessary to insert the remaining corner of the tab 20 into the remaining slot 21 and then by springing the side 14 outwardly, the tab 22 can be inserted into the triangular recess provided by the inwardly 50 disposed fold formed by the scoring 18, as above described. When the box is folded and the end tab 20 has been inserted in the slots 21 and the tabs have been inserted into the side recesses, the box will be firmly held in its closed position 55 without requiring any additional wrapping or tying, as is generally necessary with boxes of this character. If the box is constructed of foil lined blank, it will be seen that the box will provide a substantially water-tight container up to 60 the point where apex of the triangular portions 19 projects into the sides of the box.

It will be obvious that the invention may be modified in many ways, and all such modifications as fall within the terms of the appended 65 claims are considered as falling within the scope of the invention.

Having thus described my invention, what I claim and desire to secure by Letters Patent is—

1. A blank for a collapsible box of the char-

acter described comprising a single rectangular blank having longitudinally and transversely extending score lines forming the top and bottom areas of a box and cover, an infolded and secured flap at the box forming end of said blank, 5 diagonal scored lines extending outwardly from the corners of the box bottom defining a corner fold disposed beneath said flap when the sides of the blank are folded thereunder, a notched and diagonally scored portion in the sides of said blank 10 between the bottom and top forming areas thereof adapted to interfold and form corners of the connecting ends of the box and cover, a closure flap upon the cover forming area adapted 15 to be inserted in slots formed in the first formed end of said box, and a tab extending outwardly at the end of each side adjacent said closure flap adapted to be inserted in the fold formed by the diagonal scored lines terminating beneath the infolded and secured flap first above described 20 to lock the cover forming area over the box forming area when the box is closed.

2. A blank for a collapsible box of the character described, comprising a one piece rectangular blank having two longitudinally and four transversely extending score lines forming the top, bottom, ends and sides of a box and cover, an infolded and secured flap at the box forming end of said blank under which the sides and corner folds of the box forming portion of the blank 30 are disposed, a notched and diagonally scored portion in the sides of said blank between the bottom and top forming areas thereof adapted to interfold and form the corners at the hinged end of the box and cover, a closure flap upon 35 the cover forming area of said blank adapted to be inserted in slots formed in the cooperating end of said box when formed, and a tab extending outwardly at the end of each side adjacent said flap adapted to be inserted into the diagonal 40 corner folds disposed under the inturned and secured flap first above described to lock the cover forming area over the box forming area when the box is closed.

3. A one piece box blank having longitudinally 45 and transversely extending score lines forming sides, ends and spaced bottom and top forming areas of the box, a diagonal scoring at the outer end of the box forming portion permitting an inward folding at this corner of the blank, an 50 inwardly secured flap at the adjacent end of the blank adapted to engage said inwardly folded portions and hold the end and side walls of the box in an erected position, notched and diagonally 55 secured areas adjacent the space between the top and bottom forming areas adapted to interfold and form an erected corner for the remaining corners of the box when the cover forming area is folded thereover, a closure flap at the outer end of said cover forming area adapted to be 60 inserted at its corners into slots formed in the first erected end of the box, and a locking tab upon each side of the cover forming portion adapted to be projected into the recess formed by the first diagonally infolded portion to lock 65 the cover forming area over the box formed as described.

GUSTAVE A. TROST.
